United States Patent Office

Des. 180,329
Patented May 21, 1957

180,329

BOWL

Samuel M. Highberger, Oak Park, Mich.

Application August 16, 1955, Serial No. 37,499

Term of patent 14 years

(Cl. D44—15)

Fig. 1 is a view in perspective of a bowl embodying my new design;

Fig. 2 is a top plan view;

Fig. 3 is a longitudinal sectional view taken on the line 3—3 of Fig. 2; and

Fig. 4 is an end elevational view of the bowl taken from the left end thereof as viewed in Figs. 2 and 3.

I claim:

The ornamental design for a bowl, as shown.
